J. E. JOHNSTONE

BASEBALL MASK

Filed July 23, 1921

Fig. 1.

UNITED STATES PATENT OFFICE.

JAMES E. JOHNSTONE, OF NEWARK, NEW JERSEY.

BASEBALL MASK.

Application filed July 23, 1921. Serial No. 407,063.

To all whom it may concern:

Be it known that I, JAMES E. JOHNSTONE, a citizen of the United States, and residing at Newark, in the county of Essex and State 5 of New Jersey, have invented a new and Improved Baseball Mask, of which the following specification is a full disclosure.

This invention relates to base-ball masks and it has for its object to provide a mask of 10 a lighter, more reliable and more rugged construction than those heretofore available.

The conventional mask depends for its protective features on a multiplicity of wires interlaced and arranged in a complicated 15 manner. These wires must be so interwoven as to furnish ample protection for the frontal features of the wearer and at the same time provide ample areas so that the vision will be unimpaired. In order to withstand 20 the severe blows of a base-ball, it is necessary to use very heavy wire and to join the intersections very securely and likewise to use certain reinforcing elements. As a result, the conventional vizor is much heavier 25 than its appearance indicates and it admits of being gradually injured and rendered ultimately unserviceable by the successive impacts of the base-ball.

This invention contemplates the elimination 30 of wires and of their separate pieces connected in various ways, by rendering available a one-piece integral vizor in the nature of a thin shell of very light weight yet malleable metal of a nature capable of 35 being formed by a single casting operation; thereby reducing the cost and creating a more serviceable and more desirable vizor.

Other objects and advantages will be in part indicated in the following description 40 and in part rendered apparent therfrom in connection with the annexed drawings.

To enable others skilled in the art so fully to apprehend the underlying features hereof that they may embody the same in the 45 various ways contemplated by this invention, drawings depicting a preferred typical construction have been annexed as a part of this disclosure.

The drawings show in perspective a base- 50 ball mask embodying a vizor characteristic of this invention.

Referring to the drawings, A denotes the 55 vizor which is in the shape of a semi-ellipsoidal shell which is comparatively thin and which is made by a casting-operation of a suitable light-weight alloy of a non-brittle

character. This shell is formed with side-wings B and C extending outwardly and rearwardly so as to clear the ears of the user; these ear-guards being of suitable 60 length and breadth to shield the ears and to deflect a base-ball so that the user may not be injured. Extending downwardly from the crown D of the vizor is a frontal or forehead-guard E 65 which meets a transversely arched forehead-guard F; the lowermost margin G of which lies approximately in the plane of the eyebrows so as not to obstruct the vision of 70 the player. The crown or brow portion of the vizor above the marginal edge G is provided with suitable ventilating ports H and J which may be given any shape desired and which may be located accordingly in various ways. 75

The bridge-piece K extends transversely across the face of the vizor in approximately the plane of the nose so as to form a nose-guard. This strip is preferably so dimensioned and distanced from the brow-edge G 80 as to provide a large substantially rectangular opening L affording a wide and unobstructed vision for the wearer; the height of this opening being preferably about a half-inch or so less than the diameter of a 85 base-ball so that it will be impossible for any base-ball to enter said opening sufficiently to injure the user.

The lower mouth and chin portions of the vizor are preferably also ventilated in any 90 suitable manner. For example, a large opening M may be provided immediately below the nose-bridge K and, in the interests of lightness and to permit free-spitting, may be made of ample proportions. Likewise a 95 suitably shaped opening or series of openings N will be arranged in the chin-protecting portion of the vizor for purposes of ventilation. Preferably also, the lower edge of the vizor will be inturned as represented by 100 P so as to form a guard to protect the chin against up-bounding balls.

For the sake of comfort and to protect the user against transmitted shocks, the edge of the vizor will be interiorly protected by a 105 suitable marginal pad indicated by Q. This pad may be secured in place by wires or thongs passing through small apertures 1, 2, 3, etc., drilled through the margins of the vizor at suitable points. 110

The mask is held in place by means of a suitable harness consisting of a back-strap

R and a riser S; the riser being attached to the vizor through a slot *a* in its crown, and the ends of the back-strap being attached to similar slots *b* in the ear-guards.

5 It will be seen that this invention is well adapted to achieve the above enumerated objects and advantages and it may also be observed that it has the very pronounced advantage of appreciably reducing the extent 10 to which base-balls are injured by coming in contact with masks. Wire vizors present comparatively thin edges and also numerous small projections which have a tendency to cut the jacket of the ball, whereas the present 15 vizor presents comparatively few edges and it presents chiefly well-rounded and unbroken surfaces which can occasion no injury whatsoever to the ball. It has been found by experience that a vizor made in the 20 manner disclosed is very materially lighter than a vizor of corresponding size and strength made in the conventional manner.

Without further analysis, the foregoing will so fully reveal the gist of this invention 25 that others can, by applying current knowledge, readily adapt it for various utilizations by retaining one or more of the essential characteristics of either the generic or specific aspects of this invention, and, therefore, such adaptations should be, and are intended to be, comprehended within the meaning and range of equivalency of the 30 following claims:—

Having thus revealed this invention, I 35 claim as new and desire to secure the following combinations and elements, or equivalents thereof, by Letters Patent of the United States:—

40 1. A vizor for base-ball masks comprising a one-piece shell semi-ellipsoidal in shape and having two narrow elongated out-

wardly-bulged bars arranged in parallelism to form an enlarged eye-slit extending without obstruction from one side to the other side of the mask and isolated ventilating 45 ports located above and below said eye-slit.

2. A base-ball mask combining a one-piece integral vizor having a crown and rearwardly-extending ear-wings and a chin-guard and two widely-separated narrow 50 elongated outwardly-bulged bars extending in parallelism to form with said chin-guard two isolated elongated apertures extending horizontally across the face of the mask without interruption for the mouth and 55 eyes; a marginal pad; and a retaining harness attached to the crown and the ear-wings.

3. A one-piece integral vizor for base-ball 60 masks having its crown apertured for ventilation and having an enlarged face-opening sub-divided only by a single narrow transverse nose-protecting bridge extending horizontally to provide a substantially unobstructed vision to the wearer. 65

4. A base-ball mask comprising a one-piece integral vizor in the nature of a metallic shell having a single narrow transverse nose-arch devoid of vertical extensions, said vizor providing rearwardly and outwardly 70 extending ear-guards and an inturned chin-guard, the brow-portion and chin-piece having ventilating apertures; a marginal pad; and a retaining-harness secured to the brow and the ear-guards of said vizor. 75

In witness whereof, I hereunto subscribe my name, as attested by the two subscribing witnesses.

JAMES E. JOHNSTONE.
